US0D1054444S

(12) **United States Design Patent** (10) **Patent No.:** **US D1,054,444 S**
(45) **Date of Patent:** **** Dec. 17, 2024**

(54) **DISPLAY SCREEN OR PORTION THEREOF HAVING A GRAPHICAL USER INTERFACE FOR A SIMPLIFIED VISUALIZATION OF A DATA SECURITY SYSTEM**

(71) Applicant: **SPLUNK Inc.**, San Francisco, CA (US)

(72) Inventors: **Tatsuya Hama**, North Vancouver (CA); **Clark E Mullen**, San Mateo, CA (US); **Ioan Popa**, Fremont, CA (US); **Iryna Vogler-Ivashchanka**, Los Altos, CA (US)

(73) Assignee: **SPLUNK Inc.**, San Francisco, CA (US)

(**) Term: **15 Years**

(21) Appl. No.: **29/879,934**

(22) Filed: **Jul. 14, 2023**

(51) **LOC (14) Cl.** **14-04**

(52) **U.S. Cl.** **D14/485**
USPC **D14/485**

(58) **Field of Classification Search**

USPC **D14/485-495**
CPC **G06F 3/048; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/0486; G06F 3/0487; G06F 3/0488; G06F 3/04883; G06F 3/04886; G06F 3/0489; G06F 3/04892; G06F 3/04895; G06F 3/04897**

CLAIM

The ornamental design for a display screen or portion thereof having a graphical user interface for a simplified visualization of a data security system as shown and described.

DESCRIPTION

The sole FIGURE is a front view of a display screen or portion thereof having a graphical user interface for a simplified visualization of a data security system showing our new design.

The outermost broken lines depict the display screen or portion thereof and forms no part of the claimed design. The remaining broken lines depicting portions of the graphical user interface form no part of the claimed design.

1 Claim, 1 Drawing Sheet
